DESIGN FOR A HEATER OR SIMILAR ARTICLE

Eugene G. Siegler and Raymond J. Siegler,
Marion County, Ill.

Application December 3, 1938, Serial No. 81,539

Term of patent 7 years

To all whom it may concern:

Be it known that we, Eugene G. Siegler and Raymond J. Siegler, citizens of the United States, residing in the county of Marion and State of Illinois, have invented a new, original, and ornamental Design for a Heater or Similar Article, of which the following is a specification, reference being had to the accompanying drawing, forming part thereof.

The figure is an elevation in perspective of a heater, showing our new design, the other side of the heater being substantially the same as the side shown.

We claim:—

The ornamental design for a heater, or similar article, as shown and described.

EUGENE G. SIEGLER.
